VENDING MACHINE

Benjamin W. Fry, University City, Mo., assignor
to National Vendors, Inc., St. Louis, Mo., a cor-
poration of Missouri

Application September 15, 1939, Serial No. 295,005

7 Claims. (Cl. 312—55)

This invention relates to vending machines, and with regard to certain more specific features, to coin-controlled vending machines.

Among the several objects of the invention may be noted the provision of a vending machine of the class described which is adapted selectively to vend, under the control of a single coin releasing mechanism, one article out of individual supplies of a great variety of different articles; the provision of a vending machine of the class described including various article storage compartments, in relatively great plurality, which compartments are arranged along two coordinates, such as vertical and horizontal coordinates; the provision of a vending machine of the class described wherein individual ejection means are provided for each of the said article compartments, and means are provided whereby actuation of any one of the ejecting means automatically locks all of the other ejecting means against simultaneous actuation; the provision of a vending machine of the class described including means preventing improper access to or withdrawal of an article from the article storage pocket thereof; and the provision of a vending machine of the class described which is relatively simple and economical in construction, and durable, reliable, positive, and fool-proof in operation. Other objects will be in part obvious and in part pointed out hereinafter.

The invention accordingly comprises the elements and combinations of elements, features of construction and arrangements of parts which will be exemplified in the structures hereinafter described, and the scope of the application of which will be indicated in the following claims.

In the accompanying drawings, in which is illustrated one of various possible embodiments of the invention,

Fig. 1 is a front elevation of a vending machine embodying the present invention;

Figures 2, 3, 4, 5, 6 and 7 are cross sections taken substantially along lines 2—2, 3—3, 4—4, 5—5, 6—6 and 7—7 of Fig. 1, and various other figures, respectively;

Fig. 8 is a back elevation of an article storage compartment, taken substantially at the position indicated by lines 8—8 in Figures 2 and 4; and,

Fig. 9 is a cross section taken substantially along line 9—9 of Fig. 3.

Similar reference characters indicate corresponding parts throughout the several views of the drawings.

In the automatic or machine vending of certain classes of merchandise it is advisable that

there be provided, in position available for selective delivery, stores of a number of different species of the articles of the class. This observation applies particularly in the vending of printed matter, such as small books or pamphlets and magazines. Each species of the class of articles to be vended accordingly requires a separate compartment for its storage and display, and consequently each compartment requires a separate ejecting mechanism; otherwise prohibitive expense factors are involved, due to the large amount of space required for individually complete vending machines for each of the species of the class of articles. Furthermore, it is advisable, from the standpoint of practical utility in a vending machine of this type, that a single coin release mechanism be capable of freeing any one of the multiplicity of article storage compartments and associated ejecting means, to perform the vending operation. With one such coin-releasing mechanism, the user can inadvertently make no mistake in depositing his coin, for example, in the receiving slot of a compartment of articles in which he is not interested.

The space conserving feature, in a machine of this sort, is highly important. The best arrangement of article storage compartments to bring about such economy of space is for said compartments to be located or disposed along two coordinates, such as vertical and horizontal coordinates, or in both rows and ranks. In that way, a maximum number of article storage compartments is packed together in a minimum amount of space.

The present invention is believed to be the first vending machine which succeeds in providing such article storage compartments in a two-coordinate disposition, together with individual ejecting mechanisms for each of the compartments, and an interlocking system so that only one compartment out of the entire group may be operated upon the presentation of a single coin or payment.

The highly advantageous space conservation achieved in the vending machine of the present invention is primarily due to the interlocking mechanism hereinafter to be more specifically described, and such interlocking mechanism, while serving its primary function of preventing the manipulation of more than one compartment for any one payment, is nevertheless extremely simple in construction and reliable in operation.

Referring now more particularly to Fig. 1, there is illustrated a vending machine embodying the present invention. The vending ma-

55

chine as shown in Fig. 1, and in the other figures of the drawings, is, for purposes of simplicity of illustration, shown as deprived of its outer casing, that is, the box or article of furniture in which it is mounted. It will be understood, of course, that in a vending machine as it is presented to the public, such an outer casing or furniture portion is to be added to the apparatus herein specifically shown and described.

In the vending machine shown in Figure 1, nine article storage compartments separately indicated by the letters A, B, C, D, E, F, G, H and I are shown; these are arranged in groups of threes in two coordinates, horizontal and vertical. All of these compartments together occupy only approximately nine times the area, or volume, of one of the compartments. The individual compartments are arranged in rows or ranks of three compartments each (considered horizontally or vertically) there being a total of three such rows or ranks.

It will be understood, of course, that the choice of nine compartments for purposes of illustration is not to be considered as limiting the present invention; on the contrary, the principles of the present invention may successfully be used with any plurality of individual compartments preferably greater than four.

Each horizontal row of three compartments is contained in and supported on a vertical panel, made of sheet steel or the like, indicated at numeral 1. The three panels 1 thus provided are in turn mounted on vertical side panels 3, extending from the top to the bottom of the machine. Surmounting the topmost panel 1, between the side panels 3, is an ornamental, relatively shallow panel 5, and underneath the bottommost panel 1, between side panels 3, is a base panel 7. Narrow slots or gaps 9 are provided along the lower edges of each of the panels 1, the said slots 9 providing discharge openings through which the articles in the individual compartments, A, B, C, etc., may be vended.

Each compartment A, B, C, etc., has its own article ejecting mechanism, which, from the front of the machine, constitutes the handle end of a plunger or pull-bar 11. The said plungers extend through suitable openings just beneath the top edges of the panels 1 (or 7) just beneath the respective compartments they control. For example, the plunger for compartment A, designated in Fig. 1 by the special index character 11A, is located just beneath the top edge of the middle panel 1, in central position beneath the compartment A.

The panels 1 are provided with windows 13, one for each compartment A, B, C, etc., through which the individual article stored in that compartment may be displayed, or through which the total remaining supply of such article in its compartment may be viewed, together with or in the absence of a display.

Located near the bottom of the right-hand side panel 3 is a coin-receiving slot 15. Deposit of a coin in the slot 15 is effective to control the operation of the ejecting means of all of the compartments A, B, C, etc.

Referring now more particularly to Figures 2, 3 and 4, it will be seen that the inner edges of the respective side panels 3 are bent backwardly at right angles to form side supporting plates 17 and 19, at the left and right-hand sides of the machine, respectively. The outer edges of said side panels 3 may likewise be bent back, as indicated at numerals 21, to constitute rein-

forcing or supporting flanges. Similarly the top edges of side panels 3 may be bent backwardly to form reinforcing flanges 23.

Referring now more particularly to Figures 5, 4, 5 and 8, it will be seen that the top edge of each panel 1 is bent backwardly at right angles to form a supporting shelf indicated by numeral 25. In turn, the rear edges of the shelves 25 are bent downwardly at right angles to form vertical flanges 27, which are consequently disposed parallel to the panels 1. A shelf 25 and a flange 27 need not be provided for the topmost panel 1, but such elements are provided along the upper edge of the bottom panel 7.

The lowermost edge of each of the panels 1 is bent inwardly and then upwardly, as indicated at numeral 29 in Fig. 8, to form shallow channel-shaped troughs, adapted to receive and hold window glasses 31 for each of the windows 13, 20 and likewise to hold display articles, such as the book 33 shown in Fig. 6. The lower surfaces of 25 the channel-shaped flanges 29 are preferably sloped downwardly and forwardly, as indicated at numeral 35 in Fig. 6, in order to constitute means for guiding articles to be ejected into the gaps 9 through which they are delivered.

The individual article storage compartments, referring particularly to Figures 6 and 8, all comprise preferably identical light sheet metal 30 rectangular boxes or the like indicated at numeral 37. The boxes 37 have completely unobstructed open tops for loading the articles to be vended (such as the books 33 therein). The side walls 39 of the boxes 37 are ordinarily, although 35 not necessarily, solid and imperforate. The front and back walls, however, preferably comprise only relatively narrow vertical flanges 41 and 43, respectively, which are bent inwardly at right angles from the side walls 39. To increase the 40 rigidity of the front walls, however, a sheet metal angle piece 45 is preferably secured between the two flanges 41; the front edge 47 of the horizontal portion of this angle piece 45, if suitably spaced, can advantageously be used, in assembly, 45 as a means for holding the display book 33 vertical and tightly against the window glass 31. The said box front flanges 41 do not extend clear to the bottom of the box, but terminate short 50 thereof to provide a slot or opening 49 the full width of the box, through which the articles may be ejected forwardly into and through the gap 9.

The back flanges 43 are preferably likewise reinforced by a sheet metal angle piece 51 therebetween.

The bottom 53 of the box 37, from which the side walls 39 are preferably bent upwardly, is located only under the front portion of the box 37; said bottom terminates rearwardly as a downwardly-turned flange 55 which, when the box is 60 in position in the vending machine, closely overlies the flange 27 of shelf 25. The flange 55 is interrupted by a central gap 57 (see Fig. 8) to permit the passage of an ejecting mechanism hereinafter to be described. A machine screw 65 59, passing through the flange 55 and threaded into the flange 27 on shelf 25, constitutes means for securing the box in its designated position on the shelf 25. The box 39, back of the flange 55, is open-bottomed.

The boxes 37 are loaded for vending with the articles to be dispensed, such as the books 33, in vertically stacked relation therein, and the stack is preferably topped by a freely moving weight or follower 61.

In order to prevent unauthorized access to the

articles in the box 37 as by a hook inserted rearwardly through the gap 9, the bottom of each box 37 is preferably provided with a broad leaf spring 63, which extends clear across the width of the box. The front end of the leaf spring 63 is free from the bottom 53 of the box 37, and normally tends to press upwardly with its edge resting against the under surface 35 of the channel-shaped flange 29. When an article 33 is ejected forwardly, it readily pushes the spring 63 down and out of its way (see dotted-line position of delivered article 33 in Fig. 6), but the insertion of a hook, knife or the like rearwardly through gap 9 is ineffective to reach the articles 33 remaining in the stack, because such hook or the like is caught between the under side of spring 63 and the box bottom 53.

The individual article-ejecting mechanism will next be described, with reference particularly to Figures 4, 5, 6 and 8.

The plungers 11, hereinbefore mentioned, preferably comprise rectangular or square metal bars, and they slide horizontally, back and forth, in suitably provided openings in the panels 1 (or 7) and coextensive flanges 27. At their front ends, each of the plungers 11 is preferably provided with finger-grip indentations 65. The plungers 11 are of sufficient length so that, in their retracted positions, they extend back a little farther than the rear ends of the article storage boxes 37.

At its rear end, each plunger 11 is provided with a hook or pusher plate 67, of considerable width, each of which comprises a flat portion 69 and an upstanding edge 71 at the rear thereof. The upper surface of the flat portion 69 is preferably provided with grooves or indentations 73, to reduce the weight of the pusher plate, and to reduce the area of surface in frictional engagement with the article being ejected. The pushers 67 are held to the plungers 11 by means of machine screws 74, the heads of which are suitably recessed in one of the notches 73 as shown. Ears 75 extend downwardly from the pusher plate 67 and engage the opposite sides of the plunger 11, to further increase the rigidity with which these two elements are connected.

It will readily be seen (see dotted-line position in Fig. 6) that when the plunger 11 is grasped, from the front of the machine, and pulled forwardly, that the upstanding edge 71 of the pusher plate 67 engages the rear end of the lowermost article 33 of the stack in the box 37, and pushes said article forwardly off the bottom of said stack. The article 33 depresses the spring 63 and passes through the gaps 49 and 9, consecutively, the front edge of the article emerging from the front of the vending machine where it may readily be grasped and completely withdrawn by the purchaser. At the instant that a withdrawal is completed, the spring 63 snaps back into its normal position to prevent unauthorized withdrawal of another article.

The forward movement of the plunger 11, in a discharging operation, may be considered as limited by the abutment of the pusher plate 67 with the flange 27. This is clearly a sufficient movement to push an inch or more of the article out through the gap 9, so that the article may readily be grasped by the purchaser for further and complete withdrawal.

The mechanism by which unauthorized operation of more than one plunger 11 at any one time is prevented, will next be explained.

Referring again to Figures 5 and 6, it will be

seen that each plunger has secured thereto, by machine screws 77, at a point about mid-way along the length of the plunger, a vertical plate 79, which projects both above and below the plunger 11. Just below the plunger 11, the plate 79 has a rectangular notch or recess 81, and the forward extremity of the portion of the plate 79 beneath the notch 81 is bent outwardly, at right angles to the plane of the plate 79, to form a projection 83.

Freely mounted in a rotatable manner on a screw 85 threaded into the outside face of plate 79 is a hook or dog or latch member 87. The member 87 has a lower portion 89, and an upper portion 91, the upper portion 91 being recessed to form a downwardly-facing hook 93. The said upper portion 91 is preferably of considerably greater area, and hence weight, than the lower portion 89, so that the normal tendency of the member 87 as a whole is to rotate in a clockwise direction, when viewed from the aspect of Figure 6, under the influence of gravity. When the plunger 11 is in its retracted position (full lines in Fig. 6), however, the lower portion 89 of the dog member 87 abuts against the inner surface of flange 27, and this abutment holds the dog 87 rotated, against gravity, to a counterclockwise position.

Referring now more particularly to Figures 2, 3, 5 and 6, numerals 95 indicate flat horizontal locking bars each of which is continuous and unbroken and extends across under an entire horizontal row of compartments and through supporting slots 97 and 99 in the side plates 17 and 19, respectively. The slots 97 and 99 permit the bars 95 to move back and forth, in their own planes, but in directions normal to their length. In order to keep the bars 95 parallel to the front panels 1, they are provided at each end with cylindrical projections 101, which enter slots 103 in arms 105 secured firmly and non-rotatably on their other ends to relatively heavy rods 107, which rods 107 extend across the entire machine and are supported, respectively, in suitable openings in side plates 17 and 19. Because of their firm attachment to the rods 107, the arms 105 at each end of the machine are permitted to rotate only co-extensively, and through the engagement of the pins 101 in the slots 103 of said arms 105, this compels the horizontal bars 95 likewise to maintain parallelism with the rods 107, and consequently with the panels 1, throughout their forward and backward movement.

The bars 95 are normally retained at the rear extremities of the slots 97 by tension springs 109, each hooked at one end into the end of a bracket 111 supported on the rear edge of the side wall 17, and hooked at the other end into the arm 105.

Referring again to Fig. 6, it will be seen that the horizontal bar 95 normally enters the notch 81 in the plate 79 on plunger 11, and, under the influence of spring 109, normally presses said plate 79 rearwardly until it abuts the inner surface of flange 27. This engagement of the horizontal bar 95 with the plates 79 likewise serves as means for normally retracting each of the plungers 11, after it has been pulled in a dispensing operation.

The horizontal bar 95 is provided with an opening 113 in position to meet the hook 93 of each dog 87. Endwise movement of the horizontal bar 95, it will be understood, is prevented by the engagement of the ends of such horizontal

bar with the arms 105 at each end of the machine.

It will now be seen that whenever one of the plungers 11 is pulled, in a vending operation, the horizontal locking bar 95 associated with that plunger is required to move forwardly along with the plunger, because of the engagement of the notch portion 81 of plate 79 mounted on the plunger with said horizontal bar 95. The fully extended, forward position of a plunger 11, and its horizontal bar 95, is indicated in dotted lines in Fig. 6. For certain reasons to be explained hereinafter, it is important, for the proper functioning of the machine, that once this forward movement of one of the horizontal bars 95 is commenced, said movement shall be required to be continued, without any intervening reverse movement, to the full forward position of the said horizontal bar 95. For this reason each horizontal bar 95 is provided, on the inside surface of supporting side plates 19, with a full-stroke mechanism illustrated in greater detail in Figure 7, to which attention is now directed.

For the extent of its length associated with this full-stroke mechanism, each horizontal bar 95 is provided on its under surface with a series of indentations or serrations 115 running parallel to the length of the bar and preferably extending clear across the width of the bar. Numeral 117 indicates a ratchet lever that is pivoted on a screw 119 threaded into the inner surface of said supporting side plate 19. The ratchet 117 has a rectangular head 121, and at its other end it is hooked to a tension spring 123 anchored at its other end to an ear 125 struck up from the said side-plate 19. The pivot 119 is located substantially midway along the length of the slot 97, from front to back, and is consequently substantially at the mid-point of travel, back and forth, of the horizontal bar 95. When, now, the horizontal bar 95 moves forwardly, its leading edge engages the said head 121 and forces the head to rotate, in a clockwise direction as viewed from the aspect of Fig. 7, to a sloping position indicated in dotted lines, against the tension of the spring 123. The left-hand corner of head 121 then successively engages the notches or serrations 115 in the under side of the moving horizontal bar 115. Forward movement of said horizontal bar is permitted, but attempted reverse movement is unsuccessful because the ratchet is incapable of rotating, at the moment, in a counterclockwise direction, as would be necessary to permit such reverse movement. The horizontal bar 95 can thus move forwardly only, until it reaches the forward extremity of its travel, when its trailing edge passes over the head 121 of ratchet 117 and allows the ratchet to resume its normal, vertical position under the influence of spring 123. When the horizontal bar 95 commences its rearward travel, now, the ratchet 117 rotates to a reverse position, and, acting in the same general manner, but in an inverted sense, prevents a change of direction of the rearwardly moving horizontal bar 95 until it has again assumed its rearmost position, which is its normal position under the influence of its spring 109.

The latch 87 (referring again to Fig. 6) serves to lock any plunger 11 being manipulated to the horizontal bar 95 during this controlled back and forth movement of said horizontal bar 95. As soon as the plunger 11 is pulled forwardly, away from the flange 27, the weight of the upper portion 91 of dog 87 causes the hook 93 to fall

into the opening 113 in the horizontal bar 95, since the flange 27 no longer engages the lower portion 89 of said dog 87 to prevent such action. With the hook 93 thus engaged in the opening 113 in horizontal bar 95, it will readily be seen that the plunger 11 cannot be pushed back into the machine, from its extended position, without simultaneously pushing back the horizontal bar 95; and, by reason of the action of the ratchet mechanism of Fig. 7, the horizontal bar 95 cannot be pushed backwardly until it has completed a full movement to the forward end of its travel.

It will be seen, however, that the horizontal locking bar 95 in its retracted position is free of any permanent attachment to any one plunger 11. This is because the hook 93 of each plunger 11 is normally held out of engagement with said bar in the manner described except after a stroke has been started, after which the hook 93 couples into the opening 113 so that the respective plunger is prevented from being pushed in until completion of the pulling stroke. Accordingly, any one plunger 11 in a given row of compartments may be operated, causing the operation of the horizontal bar associated with that row of compartments, but such actuation does not affect the normal retracted positions of all of the remaining plungers 11 in that row. With the mechanism so far described, however, it is possible simultaneously to actuate two or more plungers in a given row, and since this is not to be desired, the mechanism provided for preventing such action will next be described.

Referring now more particularly to Figures 4 and 6, it will be seen that the shelves 25 are provided, on their under surface, with downwardly struck, oppositely facing pairs of ears 125, which serve to slidably support a composite horizontal bar, indicated generally by numeral 127, which is composed of longitudinally detached units 129. The individual units 129 are free to slide or separate with respect to each other. The units 129 are one less in number than the number of article compartments in a horizontal row; in other words, with the embodiment shown, there are two bar units 129 for the three compartments found in a horizontal row. Blocks 131, screwed or otherwise secured to the under faces of the shelves 25, serve to limit the endwise movement of the said bar units 129. The blocks 131 are so positioned that the units 129 are free to move only by a distance equal to or slightly in excess of the thickness of the upwardly projecting portions of plates 79 on plunger bars 11 (see also Fig. 6).

As indicated as numeral 133, the corners along the rear edges of each of the bar units 129 are beveled in opposite directions, so that when two bar units 129 come together, the meeting doubled portions 133 form a guiding notch.

It will now be seen that when any one of the plunger bars 11 is actuated, its plate 79, guided by the notches or gaps afforded by beveled portions 133, forces a gap for itself between adjacent bar units 129, or between the end of one of the bar units 129 and one of the stop members 131. The left-hand plate 79 in Fig. 4, for example, has forced such a gap for itself. The gap thus provided is of sufficient width to permit one such plate 79 freely to slide back and forth; but in providing this one gap, the remaining bar units 129 have been forced together and against the opposite end stop 131 in such a way that they are all locked, and the plate 79 of another plunger 11 is incapable of forcing itself a gap.

The maximum travel of the plunger 11 is such that the associated plate 79 of any one of the plungers 11 is not entirely withdrawn, forwardly, from the gap it creates; hence so long as one plunger in a given row is being operated, the other plungers in that row are locked against operation. In this manner only one plunger of a given horizontal row of compartments may be operated at any one time.

The mechanism so far described illustrates how provision is made insuring against operation of more than one plunger in a given row, but, so far as the foregoing description is concerned, no means have yet been provided for preventing the simultaneous operation of plungers of compartments in different horizontal rows. The mechanism provided for preventing such operation will next be described.

Referring now more particularly to Fig. 2, it will be seen that there are mounted, in suitable slide bearings 135 secured to the wall 17, a plurality of detached bar units 137 together constituting a composite vertical bar indicated generally by numeral 139. The bar units 137, like the horizontal bar units 129, are provided one less in number than the number of horizontal rows of compartments; in other words, for the embodiment illustrated, with three horizontal rows of compartments, there are two vertical bar units 137 provided to make up the composite vertical bar 139. A block 141 secured to the side wall 17 just beneath the lowermost slot 97 serves to limit the downward movement of the bar sections 137 of the composite vertical bar 139. Each of the bar sections 137 has its lower rear corner bevelled, as indicated at numeral 143, to provide a guiding notch.

It will now be seen that whenever one of the horizontal bars 95 moves forward in connection with the pulling of a plunger 11, it is obliged in so moving to enter the notch formed by the bevelled portion 143 and to force aside (up and/or down) one or more bar units 137, to create a gap in the bar 139 through which it may pass. However, the lengths of the bar units 137 are such that when a gap is so created by the forward movement of one of the horizontal bars 95 (such as the horizontal bar 95 of the middle row in the embodiment shown in Fig. 2), all of the bar sections 137 above the actuated horizontal bar are forced upwardly, and the upper end of each bar section is brought into a locking position across a slot 97, so that the horizontal bar 95 of that slot may not be moved forwardly. At the same time, the particular horizontal bar 95 in its gap between bar sections 137 locks all such bar sections 137 beneath it downwardly, in a position such that the lowermost bar section abuts the block 141; consequently no horizontal bar 95 below the actuated horizontal bar is able to create itself a gap in the composite vertical bar 139, and consequently no such horizontal bar below the actuated horizontal bar may be moved forwardly.

It will accordingly be seen that through the mechanism just described, only one horizontal bar 95 may be actuated at any one time; the actuation of any one such horizontal bar being effective to lock all of the other horizontal bars (and hence the associated plungers 11) against simultaneous movement.

It will accordingly be seen that with the apparatus of the present invention it is possible to actuate only one plunger 11 out of the entire group of plungers 11 at any one time, the actua-

tion of any one plunger bringing into play automatic interlocking means whereby not only can none of the other plungers in its row be operated, but none of the plungers in any of the other rows can be operated.

The mechanism by means of which the operation of the entire assembly of plungers 11 is controlled through a coin-release device will now be described.

Referring now more particularly to Fig. 3, it will be seen that there is provided, one for each horizontal row of compartments, a bell-crank lever 145 (the bell-crank lever for the lowermost row of compartments is given the separate number 147, for reasons hereinafter to be made clear), each of which levers is pivoted, at its angle or fulcrum, on a screw 149 mounted in the outer surface of side plate 19. The bell-crank levers 145 (and 147) have forward arms 151, which extend downwardly in position to move back and forth across the front end of the respective slot 99. The bell-crank levers 145 (and 147) also have rearwardly extending arms 153, all of which are pivoted at their ends, as by screws 155, to a single vertical link or bar 157. The bar 157, and the manner of its attachment to each of the bell-crank levers, provides that all of said bell-crank levers must rotate in a like manner when any one of them is moved. To the upper end of the bar 157 is attached one end of a tension spring 159, the other end of which is secured near the top of the side plate 19. The tension spring 159 tends at all times to return the bar 157 to its relatively higher position, and consequently to rotate the bell-crank levers 145 and 147 in a counter-clockwise direction, as from the solid line position of Fig. 3 to the dotted line position therein.

The ends of the unbroken horizontal bars 95 for each of the rows extend through the slots 99 a sufficient distance that, whenever one of said horizontal bars 95 is pulled forwardly, it engages the forward arm 151 of its respective bell-crank lever 145 (or 147), and such forward movement causes said bell-crank lever to undergo clockwise rotation, against the tension of spring 159, as from the dotted line position of Fig. 3 to the solid line position. For example, in Fig. 3, the horizontal bar 95 of the middle row of compartments has been pulled forward, and this has caused the entire collection of bell-crank levers 145 and 147 to rotate in a clockwise manner, retracting the vertical bar 157 against the tension of spring 159.

It will now be seen that the operation of the entire machine may be coin-controlled by interposing any suitable coin release mechanism in the system comprising the bell-crank levers 145 and 147 and the bar 157, since if the bar 157 is locked in its uppermost position, or any one of the bell-crank levers is locked in its extreme counterclockwise position, none of the horizontal bars 95 may be operated (and hence none of the plungers 11 may be operated) until after the locked condition is removed.

The connection of a suitable coin - release mechanism to the system comprising the bell-crank levers 145 and 147 and the vertical bar 157 is a simple matter. Numerous types of such coin release mechanisms may readily be adapted to obtain the desired locking and unlocking action. By way of illustration, however, a simple form of such coin release mechanism is shown in the lower part of Fig. 3, and in Fig. 9. Extending upwardly from the arm 153 of bell-crank lever 147, and centered on the screw 149, is a quadrant-shaped extension 161. The extension 161 is in

the plane of the lever 147. At its upper edge, this quadrant extension 161 is provided for a short distance with a peripheral extension 163, which rearwardly terminates as a shoulder 165. Secured to the inner face of the quadrant-shaped projection 161, at the extreme upper corner thereof, is a generally rectangular block 167, which is substantially thick enough to fill the space between the quadrant-shaped extension 161 and the wall 19. The block 167 rearwardly terminates short of the shoulder 165 by a distance somewhat less than the diameter of the coin (indicated in dotted lines by numeral 169), that is to actuate the apparatus.

Mounted immovably on the wall 19 between the bell-crank lever 147 and said wall is a guide plate 171, which in thickness is capable of substantially filling the space between said lever 147 and the wall 19. The guide plate 171 has an upper edge 173 which, for a distance, is substantially circular about the screw 149, but at a radius shorter than the radius of the quadrant portion 161 of lever 147 (to the extreme edge of extension 163) by an amount slightly less than the diameter of the coin 169. As indicated at numeral 175, the edge 173 of plate 171 rearwardly terminates as the bottom or left-side guide wall 175 of a coin delivery chute 177. A companion right-side guide wall 179 for the chute 177 is provided at a suitably spaced distance from the wall 175, and is preferably likewise mounted on the wall 19. The chute 177 delivers used coins to a suitable receptacle, such as the cup 181.

Numeral 183 indicates a latch lever of bell-crank shape, pivoted at its angle or fulcrum on a screw 185 mounted in the wall 19. The latch lever 183 is preferably of a thickness equal to the combined thicknesses of the bell-crank lever 147 and the guide plate 171. The forward arm 187 of the lever 183 normally rests on the upper edge of the quadrant-shaped extension 161, and is held firmly thereagainst by a tension spring 189 hooked at one end to the rearward arm 191 of the bell-crank lever 183, and at its other end to any convenient means, such as a portion of a coin introduction chute 193 to be described.

The coin introduction chute 193 leads coins introduced in the slot 15 on the front of the panel 3 downwardly around a suitable curve and deposits said coin, parallel to the wall 19, perpendicularly above the pivot screw 149.

The operation of the coin release mechanism thus described will now be indicated.

When the bell-crank lever 147 is in its normal position, shown in dotted lines in Fig. 3, it will be seen that attempted clockwise rotation of the bell-crank lever 147, in the absence of a suitable coin, is prevented by engagement of the end of arm 187 of the bell-crank lever 183 with the shoulder 165 formed by the right-hand end of peripheral extension 163 of quadrant-shaped plate 161. Consequently the bell-crank lever 147 cannot be rotated, and consequently none of the plungers 11 may be operated, until a suitable coin 169 is introduced.

When a suitable coin 169 is introduced into the coin slot 15, the coin introduction chute 193 directs it so that it falls vertically downwardly and comes to rest with its bottom edge resting on the top edge 173 of guide plate 171, and its front edge simultaneously rests against the rear wall of block 167. It will now be seen that the rear edge of the coin is positioned as an inclined plane, or sloping cam, alongside the shoulder 165, so that when it is now attempted to rotate the bell-crank lever 147, such rotation is possible, because the end 187 of latch lever 183 engages the sloping edge of the coin and easily rides up over the shoulder 165 onto the peripheral edge of extension 163. Simultaneously, the front edge of block 167 and quadrant-shaped plate 161 push the coin 169 rearwardly along edge 173 and into chute 177, which delivers it to the coin-receiving cup 181.

With the presentation of a suitable coin, therefore, clockwise rotation of the bell-crank lever 147 (and consequently the bell-crank levers 145) may be effected, as is a necessary operation in order to permit the pulling of any of the plungers 11, for reasons heretofore made apparent.

It will thus be seen that a single coin-release mechanism functions effectively to lock (or unlock) the entire battery of article-ejecting plungers 11.

Two springs, namely, the spring 159 tending to pull the vertical bar 157 upwardly, and any one of the springs 109 tending to pull its unbroken horizontal bar 95 backwardly, conjointly function in each instance to retract, automatically, any plunger 11 that may have been actuated in effecting a vending operation. The apparatus as a whole thus automatically restores itself to locked position immediately on the completion of a vending operation.

A feature of the machine which is to be noted is that the article-receiving boxes 37 may easily be removed from the back of the machine for reloading, simply by removing the screw 59 associated with the particular box, and then lifting said box off the shelf 25. Replacing is equally simple; no special positioning of the first or lowermost article in any box needs to be made as said box is reinserted into the machine.

It will also be noted that a plunger 11 will not function when its associated compartment is empty of articles, for then the pusher plate 71 would attempt to eject a follower 61, and the followers 61 are intentionally made too thick to pass through the discharge gaps 9.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A vending machine comprising a plurality of separate article-receiving compartments disposed in a plurality of horizontal rows arranged one on top of the other, each row containing a sub-plurality of compartments, separate means for each compartment for ejecting an article therefrom, and interlocking means locking all of the remaining ejecting means against operation when any one ejecting means is operated, said interlocking means comprising, for each said row, an unbroken horizontal bar traversing the row and coupled to each ejecting means in that row so that upon operation of any one ejecting means in said row said unbroken horizontal bar is moved normally to its length, and a vertically sliding bar consisting of a plurality of detached bar sections with a gap between adjacent vertical bar sections positioned adjacent to each said horizontal bar, the aforesaid movement of any one of said unbroken horizontal bars normally to its

length causing said unbroken horizontal bar to enter said adjacent gap and push the vertical bar sections aside vertically, said vertical bar sections sliding so that when any one of said unbroken horizontal bars has entered its gap, all of the remaining gaps in said vertical bar are closed and prevent the reception therein of any other of said unbroken horizontal bars.

2. A vending machine comprising a plurality of separate article-receiving compartments disposed in a plurality of horizontal rows arranged one on top of the other, each row containing a sub-plurality of compartments, separate means for each compartment for ejecting an article therefrom, interlocking means locking all of the remaining ejecting means against operation when any one ejecting means is operated, said interlocking means comprising, for each said row, a horizontally sliding bar consisting of a plurality of detached bar sections with a gap between adjacent bar sections positioned adjacent to each ejecting means in that row, each ejecting means having a projection thereon adapted to enter said adjacent gap and push the bar sections aside, endwise, when said ejecting means is operated, means limiting the endwise movement of all of the bar sections of each bar so that when any one gap therein is receiving a said projection, all of the other gaps are closed and prevent the reception therein of any of said projections, said interlocking means further comprising, for each said row, an unbroken horizontal bar traversing the row and coupled to each ejecting means in that row so that upon operation of any one ejecting means in said row said unbroken horizontal bar is moved normally to its length, and a vertically sliding bar consisting of a plurality of relatively movable bar sections with a gap between adjacent vertical bar sections positioned adjacent to each said horizontal bar, the aforesaid movement of any one of said unbroken horizontal bars normally to its length causing said unbroken horizontal bar to enter said adjacent gap and push a vertical bar section aside vertically, one or more of said vertical bar sections sliding so that when any one of said unbroken horizontal bars has entered a gap, all of the remaining gaps in said vertical bar are closed and prevent the reception therein of any other of said unbroken horizontal bars.

3. A vending machine comprising a plurality of separate article-receiving compartments disposed in a plurality of horizontal rows arranged one on top of the other, each row containing a sub-plurality of compartments, separate means for each compartment for ejecting an article therefrom, a single means controlling the operation of all of said separate ejecting means, interlocking means locking all of the remaining ejecting means against operation when any one ejecting means is operated, said interlocking means comprising, for each said row, an unbroken horizontal bar traversing the row and coupled to each ejecting means in that row so that upon operation of any one ejecting means in said row said unbroken horizontal bar is moved normally to its length, and a vertically sliding bar consisting of a plurality of relatively movable bar sections with a gap between adjacent vertical bar sections positioned adjacent to each said unbroken horizontal bar, the aforesaid movement of any one of said unbroken horizontal bars normally to its length causing said unbroken horizontal bar to enter said adjacent gap and push a vertical bar section aside vertically,

5 one or more of said vertical bar sections sliding so that when any one of said unbroken horizontal bars has entered a gap, all of the remaining gaps in said vertical bar are closed and prevent the reception therein of any other of said unbroken horizontal bars.

4. A vending machine comprising a plurality of separate article-receiving compartments disposed in a plurality of horizontal rows arranged one on top of the other, each row containing a sub-plurality of compartments, separate means for each compartment for ejecting an article therefrom, a single means controlling the operation of all of said separate ejecting means, interlocking means locking all of the remaining ejecting means against operation when any one ejecting means is operated, said interlocking means comprising, for each said row, a horizontally sliding bar consisting of a plurality of detached bar sections with a gap between adjacent bar sections positioned adjacent to each ejecting means in that row, each ejecting means having a projection thereon adapted to enter said adjacent gap and push the bar sections aside, endwise, when said ejecting means is operated, means limiting the endwise movement of all of the bar sections of each bar so that when any one gap therein is receiving a said projection, all of the other gaps are closed and prevent the reception therein of any of said projections, said interlocking means further comprising, for each said row, an unbroken horizontal bar traversing the row and coupled to each ejecting means in that row so that upon operation of any one ejecting means in said row said unbroken horizontal bar is moved normally to its length, and a vertically sliding bar consisting of a plurality of relatively movable bar sections with a gap between adjacent vertical bar sections positioned adjacent to each said unbroken horizontal bar, the aforesaid movement of any one of said unbroken horizontal bars normally to its length causing said unbroken horizontal bar to enter said adjacent gap and push a vertical bar section aside vertically, one or more of said vertical bar sections sliding so that when any one of said unbroken horizontal bars has entered its gap, all of the remaining gaps in said vertical bar are closed and prevent the reception therein of any other of said unbroken horizontal bars.

5. A vending machine comprising a plurality of individual article receiving compartments, individual reciprocating plungers for removing articles from the respective compartments, a continuous locking bar for all compartments, an abutment on each plunger providing connecting means between each plunger and a rearward portion exclusively of said locking bar whereby starting movement of a plunger is transmitted to the bar but starting movement of the bar cannot be transmitted to any plunger, means for enforcing a full stroke of the bar after its movement has started, and latch means between each plunger and the bar, a stop normally holding each latch open in the starting position of its respective plunger but in other positions of the respective plunger releasing the latch to connect the plunger and bar, whereby return movement of the respective plunger is prevented until full stroke movement of the bar has been effected.

6. A vending machine comprising a plurality of individual article-receiving compartments, stop means under each compartment, reciprocating plungers adapted to remove articles from

the respective compartments, a latch on each plunger, a locking bar serving all compartments and having means adjacent the respective plungers for engagement by the latches, one-way driving connections between the respective plungers and the bar, said latch means being engageable respectively with the stops to be held in released positions when the plungers are retracted, but respectively biased for engagement with the bar upon leaving the stops after plunger movement starts.

7. A vending machine comprising a plurality of individual article-receiving compartments, individual reciprocating plungers for removing articles from the respective compartments, a continuous locking bar for all compartments in a row, means biasing the bar to starting position, an abutment on each plunger providing connect-

ing means between each plunger and a rearward portion exclusively of said locking bar whereby starting movement of a plunger is transmitted to the bar but starting movement of the bar cannot be transmitted to any plunger, means for enforcing a full stroke of the bar after its movement has once started, and latch means between the respective plunger and the bar, a stop normally holding each latch open in the starting position of its respective plunger but in other positions of the respective plunger releasing the latch to connect the plunger and the bar, whereby by return movement of the respective plunger is prevented until full stroke movement of the bar has been effected, return biasing movement of the bar being adapted to return the respective operating plunger.

BENJAMIN W. FRY.
